UNITED STATES PATENT OFFICE.

WALTER T. GORDON, OF SPOKANE, WASHINGTON, ASSIGNOR OF ONE-HALF TO A. S. FETTERMAN, OF SPOKANE, WASHINGTON.

RIVETING MACHINE.

Application filed September 24, 1923. Serial No. 664,477.

To all whom it may concern:

Be it known that I, WALTER T. GORDON, a citizen of the United States, residing at Spokane, in Spokane County and State of Washington, have invented certain new and useful Improvements in Riveting Machines, of which the following is a specification.

My present invention relates to improvements in riveting machines particularly to 10 that type of machines employing a spinning head for heading the rivet, in combination with feed mechanism for setting the anvil in operative position and punching the rivet through the work, preparatory to heading 15 the rivet in the work.

The invention is herein illustrated and described as especially directed to the feed mechanism of a riveting machine employed in the manufacture of drapers or conveyers 20 for carrying straw, chaff and grain in binders, separators and other agricultural implements. As customarily used the draper comprises a web of canvas with leather strips on one side and transverse, wooden strips or 25 cleats on the opposite side of the web. The feed mechanism of the present invention is for use on machines which are employed to rivet these three elements together, but it will of course be understood that such machine may be utilized in the manufacture of 30 other articles or commodities of similar nature.

In the utilization of my invention I employ in combination with a power operated 35 riveting machine having a well known type of spinning head for heading the rivet, manually controlled feed mechanism for co-action with the spinning head, whereby the draper or work is brought to operative position and the rivet punched through the draper preparatory to the step of heading the rivet. By this means the parts of the draper or work are securely fastened without danger of splitting the wood cleat or injury to other parts of the draper, and rapidity and accuracy in the operation of the machine are accomplished. The invention consists in certain novel combinations and arrangements of parts as illustrated in 40 the accompanying drawings wherein I have illustrated one complete embodiment of my invention, the parts being combined and arranged according to the best mode I have thus far devised for the practical application of the principles of my invention.

Figure 1 is a view in side elevation of an electrically operated riveting machine equipped with my improved feeding mechanism, the parts being shown in inoperative position.

Figure 2 is a top plan view of the machine, showing in dotted lines the position of the draper or work to be operated on.

Figure 3 is a vertical sectional view of the machine, with parts shown in elevation.

Figure 4 is a perspective view of the frame, detached, for supporting the operative parts of my feed mechanism.

Figure 5 is an enlarged, front elevation at the head of the machine.

Figure 6 is an enlarged detail view of the cam and lever mechanism for elevating the anvil and operating the punch which feeds the rivet to the work.

Figure 7 is a detail sectional view of a part of the draper showing a completed rivet joint.

Figure 8 is an enlarged, vertical sectional view of the anvil and punch, or driver.

In order that the relation of parts may readily be understood I have shown in the assembly views Figs. 1 and 3 so much of the riveting machine as is necessary for this purpose.

The machine is supported from the bed 85 plate 1 and main frame 2, and is operated by the electric motor 3 through the driving belt 4, pulley 5 and spindle 6. The spindle is rotated and reciprocable and is supported in bearings 7 at the head of the machine. 90 The rivet-heading tool 8 at the lower end of the spindle rotates with the spindle to spin and form the head of the rivet and co-operates with the angular plate 9 attached to the frame-head through the guide plate 10 which is provided with an opening or hole 11. By depressing the pedal 12 the spinning tool 8 is forced down to operative position within the opening 11 for co-action with an anvil as will be described. Suitable means 100 are employed for transmitting the motion of the pedal to the spinning tool, as for instance spring 13 which normally holds the pedal in uplifted position, the connecting rod 14, link mechanism 15, a lever 16 which is pivoted at 17 in the frame of the machine, and the head 18 on the lever which operatively engages the spindle to permit its rotation and to impart a reciprocatory motion thereto. Thus it will be apparent that 110

the spinning tool as it is rotated may be depressed by action of the pedal 12 and is returned or retracted to uplifted position by action of the spring 13.

5 While the machine is adapted for other work I have specifically illustrated herein the construction of a draper as seen in Figs. 2 and 7 in the manufacture of which the machine is particularly applicable. The 10 draper comprises a canvas web 19 to one side of which are secured longitudinal leather strips or belting 20, and at the opposite side of the canvas web are secured transversely disposed wood cleats or draper sticks 22.

15 The cleats as seen in Fig. 7 are provided with counter-bored recesses 22^a and the rivets 22' are punched through the leather, canvas and strip or cleat with the head 23 of the rivet forced into the leather belting or strip. A washer 24, which is placed in the recess for co-action with the head 25 of the rivet which is spun from the upper end of the rivet shank by the operation of the spinning tool 8 in well known manner.

20 25 The feed mechanism for presenting the work to the spinning tool is supported in a hollow frame 26 secured to the main frame of the machine as by bolts 27, and the angular portion 28 of this supporting frame is fashioned with a circular opening 29 in its top plate 30, located directly below the spinning tool as indicated in the drawings.

30 35 Manually controlled means are employed for actuating the feed mechanism, which mechanism includes a vertically disposed shaft 31, axially aligned with the spindle 6 and below the same. This shaft or bar 31 is designed to be reciprocated vertically and guided in the aligned openings 29 and 32 of the frame 30, and held against rotation by means of the guide key 33 co-acting with the wall of the opening 32.

40 45 At the head of the bar is seated an anvil 34 having a socket 34' to fit over the head of the bar, and the anvil is adapted to support the draper or work while being riveted by the spinning tool 8. In its upper end the anvil carries a bushing 35 which is resiliently supported in its recess 36 on the spring 37, and suitable means are utilized to prevent the spring, which is under tension, from forcing the bushing entirely from its pocket or recess.

50 55 The resiliently supported guide bushing 35 surrounds the upper end of a punching tool 38 which is rigidly fixed in the anvil centrally thereof, and as seen in Fig. 8, the rivet 22' is placed in the bushing with its head resting on top of the punching tool, in order that when the anvil is elevated as will be described the bushing will guide or maintain the rivet in proper position to be inserted in the draper and punched therethrough. Thus it will be apparent that the 60 upper face of the bushing is designed to con-

tact with the lower face of the draper or of the leather belting on the canvas web, and as the bar 31 is elevated the resiliently supported bushing is pushed into its pocket. As the bushing is retracted the rivet is punched or forced into the draper and as the draper is held against upward movement by the plate 10, the rivet shank is passed through the draper and its washer 24. Then the spinning tool by its action on the upper end of the shank of the rivet, spins a head on the rivet as indicated at 25 in Fig. 7. The feed bar 31 is then lowered and the draper is moved to position for a repetition of this riveting action. If necessary the top 80 face of the punching tool or anvil 38 may be corrugated as by radial lines for frictional engagement with the head 23 of the rivet to prevent rotation of the latter while the spinning tool is operating.

85 The non-rotatable reciprocable bar 31 is fashioned with an upper cross head 39 just below the anvil 34 and this cross head which is fixed to the bar is fashioned with horizontally projecting trunnions 40. A pair of links 41 having slots 42 at their upper ends are connected with the trunnions, and at their lower ends these links are pivotally connected with a pair of crank arms 43, one at each side of the bar 31 and fixed on the 90 crank shaft 44. The horizontally disposed crank shaft 44 is journaled in bearings in the frame 30 and is provided with a hand lever 45 for actuating the bar 31 through this described connection, to elevate the anvil and the punching tool carried thereby. By turning the lever to the right in Figs. 3 and 6 it will be apparent that the shaft 44 is rocked, the arms 43 swing with the shaft, and the links 41 connected with trunnions 40 95 of the cross head 39 force upwardly the bar 31 and its anvil. By the utilization of the 100 slots 42 in the links 41 a further, but slight elevation may be imparted to the bar 31 and the anvil, in order that the weight or load 105 on the anvil, as the spinning tool operates, may be shifted from the links to a more stable support.

110 For this purpose I utilize a fixed collar 46 having a second cross head 47 located below the cross head 39 and rigid with the bar 31. A pair of anti-friction rollers 48 are journaled on the cross head 39 for co-action with the pair of arcuate cam plates 49 that are loose on the rock shaft 44. The lever 115 45 which is rigid with the rock shaft is adapted to be rigidly connected with the cams or cam plates, which are slotted at 50, by means of a pin 51 carried by the lever and projected into these slots 50. The slots 120 42 in the links 41 and the slots 50 in the cam plates 49 are positioned and arranged with relation to the trunnions 40 and pin 51 125 in such manner that the first or initial movement of the lever will elevate the anvil 130

- through the connection with the upper cross head 39. Then by a continued movement of the lever the cam plates through the pin connection and rollers 48 relieve the load 5 from the links, whose slots 42 permit this additional movement, and the load is directly supported on the cams through the rollers on the lower cross head. Thus, after the anvil has been elevated to position for 10 co-action with the spinning tool, the weight of the load to be imposed on the anvil is shifted from the links to the cam connection and support. When the spinning tool is lowered to operative position and is spinning the head on the rivet the pressure on the lever 45 is relieved and the operator who has control of the lever will not be required to resist as great a strain as would be the case were the load on the links 41.
- 20 Vertically adjustable bearing blocks 52 may be provided for the rock shaft and these bearing blocks may be elevated or lowered in connection with the slots 53 in the frame 30, in order that the feed mechanism 25 may be adjusted with precision for the performance of its functions.

From the above description taken in connection with my drawings it will be apparent that I have provided in combination 30 with the riveting machine a simple but effective feeding device which may be manipulated with facility by the operator for reliable, rapid, and accurate performance of its required functions. The electrically operated machine may be controlled through the pedal mechanism and the feeding mechanism by manually operated means under the attention of a single operator who thus has the entire machinery under his direction.

40 Having thus fully described my invention, what I claim as new and desire to secure by Letters Patent is—

1. The combination in a riveting machine 45 with a supporting frame of a reciprocable bar and an anvil thereon, a guide bushing having a resilient support in said anvil, and a punching tool in said anvil and bushing adapted to support a rivet.
- 50 2. The combination with a reciprocable bar and a work retaining plate, of an anvil secured at the upper end of the bar, said anvil having a recess and a resiliently sup-

ported depressible bushing carried by said anvil in said recess, and a punching tool 55 fixed in the anvil and disposed within said bushing to support a rivet therein.

3. The combination with a work retaining plate of a reciprocable bar having a resiliently supported depressible member and a 60 relatively fixed punching member adapted to support a rivet, means for elevating said bar, and co-acting means for imparting an additional movement to said bar whereby said bar is stabilized in its elevated position. 65

4. The combination with a work-abutment, of a reciprocable anchor-bar having a resiliently supported abutment member, a rock shaft and means for operating it, means actuated from said shaft for elevating said bar, and co-acting means actuated from shaft for imparting an added movement to said bar whereby the latter is stabilized in its elevated position. 70

5. The combination with an abutment 75 member, of a reciprocable anvil bar having a cross head and trunnions thereon, a rock shaft and lever therefor, crank arms on said shaft and slotted links connecting said arms and trunnions, and means co-acting with said lever and bar for imparting an added movement to said bar whereby the latter is stabilized in its elevated position. 80

6. The combination in a riveting machine 85 with an abutment member, of a reciprocable anvil bar having a pair of fixed spaced cross heads, trunnions on one cross head and anti-friction rollers journaled on the other cross head, a rock shaft having a pair of rock arms, slotted links connecting said arms and 90 trunnions, a pair of cam members on said shaft for co-action with said rollers, a lever for operating the shaft, and a pin on said lever having a slotted connection with said cam members. 95

7. The combination with a work retaining plate, of a reciprocable anvil supporting bar having a resiliently supported depressible member and a relatively fixed anvil member adapted to support a rivet, means 100 for elevating said anvil bar and co-acting means for imparting an additional movement to said bar whereby said bar is stabilized in its elevated position.

In testimony whereof I affix my signature.

WALTER T. GORDON.
